UNITED STATES PATENT OFFICE.

WILLIAM ELIOT BARROWS, OF PHILADELPHIA, PENNSYLVANIA, ASSIGNOR
TO THE WELSBACH LIGHT COMPANY, OF GLOUCESTER CITY, NEW
JERSEY.

DESIGN FOR A GALLERY FOR INCANDESCENT LIGHTS.

SPECIFICATION forming part of Design No. 26,148, dated October 6, 1896.

Application filed May 21, 1896. Serial No. 592,481. Term of patent 14 years.

To all whom it may concern:

Be it known that I, WILLIAM ELIOT BARROWS, a citizen of the United States, residing at the city of Philadelphia, in the county of Philadelphia and State of Pennsylvania, have invented and produced a new and original Design for a Gallery for Incandescent Gas-Lights, of which the following, taken in connection with the accompanying drawings, is a specification.

Figure 1 is a top or plan view of a gallery embodying the shape or configuration which constitutes my design, and Fig. 2 is a sectional view taken on the line 2-2 of Fig. 1.

The leading features of my design comprise brackets which are fork-shaped or bifurcated in configuration, a ring shaped to form a channel, in other words a channel-shaped ring, and foliated collars.

The shape or configuration of the complete

gallery is to be best understood by reference to the drawings, in which—

a are the brackets, bifurcated or fork-shaped and having one of their branches *c* curvilinear in form.

c are perforations in the brackets *a*.

f are the collars, foliated as at *g*.

j is the channeled ring.

What I claim as new, and desire to secure by Letters Patent, is—

The design for a gallery for an incandescent gas-light, substantially as shown and described.

In testimony whereof I have hereunto signed my name in the presence of two witnesses.

WILLIAM ELIOT BARROWS.

Witnesses:

F. H. MACMORRIS,

F. A. JAMES.
